UNITED STATES PATENT OFFICE.

RICHARD MALLET, OF PARIS, FRANCE, ASSIGNOR TO THE ENSIGN BICKFORD CO., OF SIMSBURY, CONNECTICUT.

ADAPTER FOR DETONATING FUSES OR INSTANTANEOUS MATCHES.

Application filed September 21, 1928, Serial No. 307,524, and in France September 23, 1927.

Adapters for detonating fuses or instantaneous matches have already been proposed in which a block of explosive of the same or like nature as that contained in the detonating fuse or instantaneous match is compressed, usually into cylindrical shape. The blocks thus constituted are provided at their faces with a number of holes into one of which is introduced priming intended to start off the mine, while into the other holes are introduced the ends of detonating fuses leading to the mine holes to be exploded simultaneously.

The adapters thus formed require more explosive material than is strictly necessary. Also, they offer an insufficient resistance to shocks sustained while handling, for example, from falls. Again, since the holes must be made larger than the priming and the detonating fuses so that they can pass easily into the holes there is a risk that the priming, extended as it is, the match and the detonating fuses will not remain in their corresponding holes. The result may be that either the charge or some of the blasts do not explode.

The present invention has for its object an adapter of this type, but which does not present the above disadvantages. The quantity of explosive which constitutes it, is reduced to the strict minimum compatible with a good transmission of the explosion to the different fuses or instantaneous matches which are there united and with the requisite strength of the adapter to resist shocks. In addition, according to one form of the invention, the adapter is protected efficiently against humidity as well as against shocks. Finally, according to another form it is provided with simple and efficient means for ensuring the retention of the priming and of the ends of the fuses in the holes.

The advantages mentioned above are obtained in the present invention by making the holes in opposite faces so that the inner ends of the holes in one face extend in an axial direction beyond the corresponding ends of the holes in the other face.

According to a modification the block of explosive is enclosed in a metal sheet which is clamped or soldered forming a sort of double bottomed box, holes being pierced in this bottom corresponding to holes provided in the block of explosive. Washers of paper, gummed cloth or other equivalent substances capable of being easily torn away can be ap-

plied so as temporarily to stop the holes. Finally, the edges of the holes in the bottoms of the metallic envelope may be provided with small points or small hooks directed inwardly so as to secure the priming or the fuses introduced into the holes.

The accompanying drawings represent by way of example, various forms of the invention. In these drawings:

Figure 1 is a diametric section through A—A of Fig. 2 of one form. Fig. 2 is a plan view looking down on Fig. 1. Fig. 3 is a diametric section through B—B of Fig. 4, Fig. 4 is a plan view from above of Fig. 3. Fig. 5 is a diametric section of another form.

As shown in Fig. 1 the adapter is composed of a cylindrical block of compressed explosive 1 which has at one end a central hole 2 and a series of holes 3 (in this case three holes) arranged round the hole 2. On the other face and arranged in staggered relation to the holes 3 are three other holes 4. The holes are preferably separated by an equal angular distance on each face. Thus at the ends of the adapter which are the most delicate parts, there is a maximum thickness of explosive between the various holes. Also by arranging the holes of one face with respect to the holes in the other face so that the inner ends of the holes extend beyond one another the necessary amount of explosive is reduced without diminishing its solidity appreciably.

Fig. 2 represents an adapter 1 of the same type surrounded by a metal envelope 5 provided with two covers 6 and 7 which are clamped or soldered to the envelope 5 so as to enclose the block and protect it from damp and shocks. On the covers 6 and 7 as shown in the figure there may be stock washers 8 and 9 of paraffin paper or cloth backed paper, gummed cloth or any other equivalent substance which may readily be torn off without leaving portions thereof so as to uncover the holes 2, 3 and 4 for use. This washer may comprise a lug for detaching.

In order to retain the priming and also the ends of detonating fuses in the adapter, there are preferably provided on the edges of the holes in the bottoms 6 and 7 small points or hooks, such as 10. These hooks will catch the priming and will on the other hand enter the soft metallic envelope of the detonating fuse or of the instantaneous match, thus holding, once the priming and the ends of fuses or of matches have been placed in the adapter.

This method of fixing has as is known a capital importance for it is necessary not only that the fuses or the priming should not be disengaged from the adapter, but that they should, as far as possible, touch the bottom of the holes at the moment when the explosion of the adapter takes place.

In order to make the adapter fully damp-proof without having to solder the bottoms 10 7 and 8 on the envelope 5, the junction between the bottoms and the envelope may be covered by a Chatterton band 11 or a similar material as is shown in Fig. 5.

The present adapter, when it is provided 15 with retaining devices as in Figs. 3 and 4 permits of an appreciable economy in fuse or instantaneous match when compared with known adapters. In fact, it is easy to arrange it with its axis parallel to the working surface and against this latter which enables the junction between the adapter and the charges to be made with the smallest possible length of fuse.

What I claim is:

25 1. Adapter for detonating fuses or instantaneous matches consisting of a block of compressed explosive material having holes bored into the said block from opposite faces, said holes being adapted to receive the priming of the match for detonating and the ends of the detonating fuses or instantaneous matches for discharging blasting material, the holes in one face being arranged in staggered relation to those in the other.

35 2. Adapter for detonating fuses as claimed in claim 1 wherein the inner ends of the holes in the one face of the block extend beyond the inner ends of the holes bored in the other face.

40 3. Adapter for detonating fuses or instantaneous matches consisting of a block of compressed explosive material having holes bored into the said block from opposite faces, said holes being adapted to receive the priming of the match for detonating and the ends of the detonating fuses or instantaneous

matches for discharging blasting material, the holes in one face being arranged in staggered relation to those in the other, and a metal casing enclosing the block, said casing being pierced with holes corresponding to those in the block.

4. Adapter for detonating fuses or instantaneous matches consisting of a block of compressed explosive material having holes bored 55 into the said block from opposite faces, said holes being adapted to receive the priming of the match for detonating and the ends of the detonating fuses or instantaneous matches for discharging blasting material, the holes in one face being arranged in staggered relation to those in the other and the inner ends of the holes in the one face of the block extending beyond the inner ends of the holes in the other face, and a metal casing enclosing the 60 block, said casing being pierced with holes corresponding to those in the block.

5. In an adapter as claimed in claim 3 the provision on the edges of the holes in the metal casing of fuse retaining means. 70

6. In an adapter as claimed in claim 4 the provision on the edges of the holes in the metal casing of fuse retaining means.

7. In an adapter as claimed in claim 3 wherein the edges of the holes in the metal 75 casing are provided with fuse retaining means, a removable flexible cover for protecting the holes in the casing.

8. In an adapter as claimed in claim 4 wherein the edges of the holes in the metal 80 casing are provided with fuse retaining means, a removable flexible cover for protecting the holes in the casing.

9. In an adapter as claimed in claim 3 the provision of a damp-proof protector adapted 85 to cover the joints in the casing.

10. In an adapter as claimed in claim 4 the provision of a damp proof protector adapted to cover the joints in the casing.

In testimony whereof I have signed this 90 specification.

RICHARD MALLET.
